FACEPLATE FOR A BELT BUCKLE OR THE LIKE

Luca Fantaccione, Attleboro, Mass.

Application September 20, 1949, Serial No. 5,091

Term of patent 7 years

(Cl. D17—1)

To all whom it may concern:

Be it known that I, Luca Fantaccione, a citizen of the United States, residing at Attleboro, in the county of Bristol and State of Massachusetts, have invented a new, original and ornamental Design for a Faceplate For a Belt Buckle or the like, of which the following is a specification, reference being had to the accompanying drawing, forming a part hereof wherein

Fig. 1 is a plan view of a face plate for a belt buckle, illustrating the design,

Fig. 2 is a rear view of the same,

Fig. 3 is an end view of the same.

The essential features of my design reside in the parts shown in full lines.

I claim:

The ornamental design for a faceplate for a belt buckle or the like, as shown and described.

LUCA FANTACCIONE.
